UNITED STATES PATENT OFFICE.

CHARLES A. DIXON, OF NEWARK, NEW JERSEY.

HOISTING APPARATUS.

No. 920,930.

Specification of Letters Patent.

Patented May 11, 1909.

Application filed January 20, 1909. Serial No. 473,223.

To all whom it may concern:

Be it known that I, CHARLES A. DIXON, a citizen of the United States, residing at Newark, in the county of Essex and State of New Jersey, have invented certain new and useful Improvements in Hoisting Apparatus; and I do hereby declare the following to be a full, clear, and exact description of the invention, such as will enable others skilled in the art 10 to which it appertains to make and use the same, reference being had to the accompanying drawings, and to figures of reference marked thereon, which form a part of this specification.

15 This invention relates to a device adapted for hoisting, and for automatically retaining the hoisted element so as to relieve the hoisting means of its weight, and to also prevent the return or descent of the hoisting element.

20 The invention is applicable to a number of uses, but is particularly designed for use in conjunction with dwellings where the delivery of merchandise is made, particularly groceries and so forth, which deliveries are 25 made sometimes in the early morning before the occupants are about, and the merchandise can be hoisted to an upper window and left there without any chance of its being removed except by the occupants. This apparatus will therefore overcome and avoid the 30 thefts that occur in localities where two family or three family houses are situated, and where material is left on a door-step or similar situation easy of access, and therefore 35 easily stolen.

The device is illustrated in the accompanying drawing, in which—

Figure 1 is a view of the apparatus secured to the second story of a structure, and with 40 a receptacle about to be hoisted. Fig. 2 is a side view of the hoisting and retaining devices. Fig. 3 is a front view of Fig. 2. Figs. 4 and 5 are a side and an end view, respectively, of a modified form which also embodies 45 an apparatus for releasing the hoisting line after the hoisted element is in its retained position.

The device is adapted to be attached to any convenient part of a structure 10 and is 50 preferably disposed alongside the window of the upper floors of houses containing more than one family.

The device consists of a bracket 11 which projects from the base-plate 12 and preferably has the arm 13 to strengthen it. In the 55 preferred form the ears 14 project down-

wardly from the bracket 11, and between these ears 14, which act as a bracket therefor, is arranged the pulley 15 over which passes the rope or similar flexible line 16 which also passes over a pulley 17 which is arranged between the ears 18 on the base-plate 12, and then extends downwardly as shown in Fig. 1 and can be left to hang loosely, or preferably is secured to the structure so as not to 60 run free over the pulleys. 65

Below the bracket 11 is a retaining bracket 19 which has the brace 20 for strengthening it, and the bracket 19 is provided with an eye or its equivalent, which 70 eye has the opening 21 therein, which opening is substantially perpendicular with the outer edge of the pulley 15 so that when the end of the line 16 depends, it passes substantially through the center of the eye on the 75 end of the bracket 19.

A catch 22 is secured to the end of the line 16 and it has a hook 23 or similar means by which it is adapted to support an element 24 to be hoisted. The catch 22 is provided with 80

means which are adapted to pass upwardly through the eye on the end of the retaining bracket 19, but which are prevented automatically from passing downward unless manually manipulated at the top, and the 85 catch therefore suspends the hoisted element in position until released. The catch is preferably made with the wings 25 arranged on opposite sides of the catch and pivoted to the lugs 26, and having the noses 90

27 to come up against the sides of the catch to limit the movement of the wings 25. The wings therefore can collapse downwardly and nearly against the sides of the catch 22, and are thus unable to pass 95 through the eye in the end of the retaining bracket 19. When they pass through the eye they are pressed downward and inward against the springs 28, and as soon as the ends of the wings are through the opening 21, the springs 28 snap the wings apart and they rest on the top end of the eye, and when a pull on the line 16 is relaxed, the wings set 100 in place as shown in Fig. 2 and it is impossible to again lower the catch, and the device 105 is suspended thereon.

This apparatus can be used in a number of situations, and securely elevates a device without any chance of its being again lowered unless manipulated from the top.

A catch that is designed to release the line after the hoisted element is suspended is

shown in Figs. 4 and 5. The catch in this form comprises the body portion 29 having the wings 30 operating as in the previously described structure, and having the springs 31 to force them apart after they are through the eye of the retaining device, and above the wings 1 pivot one or both rods 32 which have the semi-circular portions 33 on their ends, which, when fitted together, form a ring as shown in Fig. 4, these being normally pulled together by the spring 34. The ends of the rods 32 are bent to form projecting fingers 35 and noses 36, and they are forced inward as in dotted outline in Fig. 4 to cause the semi-circular portions 33 to separate, and a ring 37 or any other equivalent, on the end of the line 16, is at once released and can be lowered for another package, and in this way catches can be alternated on the same line, or a series of catches can be used to successively hoist elements in place and leave them elevated.

Having thus described my invention, what I claim is:

1. A device of the kind described comprising a hoisting means having a flexible line thereon, a retaining means, a catch on the end of the line to be hoisted through the retaining means, and means on the catch for automatically engaging the retaining means to prevent the descent of the catch.

2. A device of the kind described comprising a plate having a bracket thereon, hoisting means on the bracket, a flexible line passing over the hoisting means, a retaining bracket having an opening therein, a catch on the end of the line adapted to pass through the opening in the retaining bracket, and means on the catch for automatically engaging the top of the retaining bracket to prevent the descent of the catch.

3. A device of the kind described comprising a hoisting means, a retaining means, and a catch on the end of the hoisting means for engaging the retaining means and being adapted to pass freely through the retaining means in an upward direction and being of a structure to prevent its descent after said upward passage.

4. A device of the kind described comprising a plate having a hoisting bracket thereon, a retaining bracket below the hoisting bracket, a pulley on the hoisting bracket, a flexible line passing over the pulley, a catch on the end of the line, and means on the catch for engaging the retaining bracket to prevent the descent of the catch.

5. A device of the kind described comprising a base-plate, a hoisting bracket thereon, a retaining bracket having an opening therein, a pulley on the hoisting bracket, a line passing over the pulley and adapted to substantially pass through the center of the eye on the retaining bracket, a catch on the line, wings on the catch, the wings being pivot-

ally secured to the catch and normally hanging downward, and means for limiting the upward swing of the wings.

6. A device of the kind described comprising a base-plate, a hoisting bracket thereon, a retaining bracket having an opening therein, a pulley on the hoisting bracket, a line passing over the pulley and adapted to substantially pass through the center of the eye on the retaining bracket, a catch on the line, wings on the catch, the wings being pivotally secured to the catch and normally hanging downward, means for limiting the upward swing of the wings, and springs beneath the wings and adapted to be compressed by the wings when the wings pass through the eye of the retaining bracket.

7. A device of the kind described comprising a hoisting bracket, a retaining bracket having an opening therein, a pulley mounted on the hoisting bracket, a flexible line on the pulley, the line passing through the opening in the retaining bracket, a catch suspended on the line, wings pivotally mounted on opposite sides of the catch, springs underneath the wings and adapted to be compressed by the wings when the wings pass through the opening in the retaining bracket, noses on the wings and arranged to engage the side of the catch to limit the upward swing of the wings, and means on the end of the catch for suspending an element.

8. A device of the kind described comprising a base-plate, a hoisting bracket mounted on the base-plate, a retaining bracket mounted on the base-plate, parallel integral ears on the hoisting bracket, a pulley mounted between the ears, integral ears on the base plate, a pulley mounted between the ears on the base-plate, a flexible line passing over the pair of pulleys, a retaining bracket having an opening therein, a catch suspended on the line, means on the end of the catch for suspending an element, wings pivotally mounted on opposite sides of the catch, springs arranged to spread the wings slightly from the catch, and means for limiting the upward swing of the wings.

9. A device of the kind described comprising a hoisting bracket, a flexible means passing over the hoisting bracket, a retaining bracket, a catch on the end of the flexible means adapted to engage the retaining bracket, means on the catch for engaging the retaining bracket to prevent the descent of the catch, and means for releasing the line from the catch when the catch is supported by the retaining bracket.

10. A device of the kind described comprising a supporting bracket having a pulley thereon, a flexible line passing over the pulley, a retaining bracket, a catch, means for suspending the catch from the line, means on the catch to permit the upward passage of the catch in its relation with the retaining

bracket, but preventing the downward movement of the catch, and means for releasing the connection between the catch and the line when the catch is suspended by the 5 retaining bracket.

11. A device of the kind described comprising hoisting means, a retaining bracket, a catch on the hoisting means adapted to engage the retaining bracket to be supported thereby, and means for automatically releasing the catch from the hoisting means when it is suspended by the retaining bracket. 10

12. A device of the kind described comprising a hoisting means, a retaining bracket, a catch on the hoisting means, the retaining bracket having a perforation through which the catch is adapted to be spread to be suspended on the edge of the perforation in the 20 retaining means, and means for connecting the catch and the hoisting means, which means are capable of being disconnected when the catch is suspended on the retaining bracket.

25 13. In a device of the kind described, a catch comprising a body portion, wings pivotally mounted on opposite sides of the catch, bars pivotally mounted in the catch

and having opposed semi-circular portions to form an eye when they are assembled, 20 fingers on the rods, a spring to hold the semi-circular portions together, and noses on the wings to engage the fingers of the rod to spread the semi-circular portions when the wings are swung upward. 35

14. In a device of the kind described, a catch comprising a body portion, wings pivotally mounted on opposite sides of the catch, bars pivotally mounted in the catch and having opposed semi-circular portions 40 to form an eye when they are assembled, fingers on the rods, a spring to hold the semi-circular portions together, noses on the wings to engage the fingers of the rod to spread the semi-circular portions when the 45 wings are swung upward, and springs secured to the body portion and adapted to be compressed by the downward swinging of the wings.

In testimony that I claim the foregoing, I 50 have hereunto set my hand this 16th day of January 1909.

CHARLES A. DIXON.
